UNITED STATES PATENT OFFICE.

ARTHUR SIDNEY PETERS, OF MANCHESTER, ENGLAND.

INK OR FLUID RECEPTACLE.

1,098,636.

Specification of Letters Patent. Patented June 2, 1914.

Application filed September 7, 1912. Serial No. 719,093.

To all whom it may concern:

Be it known that I, ARTHUR SIDNEY PETERS, a subject of the King of Great Britain, residing at 53 Camp street, Lower 5 Broughton, Manchester, in the county of Lancaster, England, have invented a new and useful Improvement in or Relating to Ink or Fluid Receptacles, of which the following is a specification.

10 The improvement relates to ink receptacles wherein is maintained a constant level of fluid during use.

I provide a reservoir for the ink having a clear opening at one side or portion of its 15 surface which is capable of being closed by a plug or cover provided with an opening therein. This plug communicates with a dip chamber formed integrally with the plug, which chamber extends in a downward 20 direction to within a short distance of the bottom of the reservoir. A horizontal passage from the dip chamber makes communication between the same and the reservoir containing the ink.

25 The plug and dip chamber may be provided with a rubber washer or band, to effect an air tight joint, or be suitably attached to said vessel. The vessel may be conveniently filled by placing the same with the cap up- 30 permost, and removing the latter, instead of providing an additional filling opening, formed in normal conditions with an air tight joint, whereby the cap referred to need not be removed except for cleaning purposes.

35 If desired, the cap and hood may be mounted separately.

With reference to the accompanying drawings, Figure 1 is a side elevation of a reservoir provided with a combined plug 40 and specially provided dip chamber, according to one form of my invention, said vessel being suitable for containing ink, and Fig. 2 is a sectional view of said plug and dip chamber. Fig. 3 is a front view of Fig. 1, and Fig. 4 is an under plan view of Fig. 2. Fig. 5 shows the combined parts of Fig. 1 when the vessel is in a tilted position.

45 *a* is the reservoir to be supplied with ink, *b* the plug, and *c* the dip chamber.

50 In Fig. 2 and according to my invention the dip chamber *c* is provided with an extension *c*¹ having a cavity *c*² at the under side, leading to the hole or passage *k* in communication with the air space *d* within 55 the dip chamber *c*. The lower portion of

said space, up to the level of the top part of the hole *k*, or thereabout, may form the ink "well" space; or the wall between the two levels of ink, as in the case of Fig. 2 be furnished by the inserted hood.

60

In the various figures the plug *b* is shown provided with a rubber or like band *l* for making an air tight joint with the vessel *a*, when the plug and dip chamber are in position therein. In the present instance, the 65 said plug is shown capable of being pressed into position instead of being otherwise attached to said vessel *a*.

In Fig. 2 the part forming the aperture *e* or opening in the plug *b* is provided, more 70 or less around the inner portion of the same, with a projecting rim or lip *m*, as an additional means for preventing the escape of the ink, such as any which may be at the bottom of the space *d*, and should the vessel *a* 75 be tilted, as indicated in Fig. 5. The level *x*, *y*, of the ink in the said vessel *a* may be such that, on account of the vacuum or partial vacuum above said level, the level of the ink for dipping purposes is, if desired, 80 situated at one of the positions already indicated, when the tendency will be for such level to be maintained in the "well" on the removal of the ink by the insertion of a pen, as is well understood.

85

In Fig. 2 the positions and forms of the extension *c*¹, tunnel or cavity *c*², and hole *k* therein, have the effect of preventing sediment entering the space *d* during the use of the vessel. It will also be seen that when the 90 vessel *a* is tilted, the fluid therein will tend to flow around the external parts of the dip chamber *c*, as well as into the lower part of the air space *d*; so that when the vessel *a* is further tilted, the fluid in the said space 95 *d* will rise until it closes the inner end of the opening *k*, while the cavity portion *c*¹, *c*², of the dip chamber *c* will project above the altered level of the fluid in the vessel *a*, thus having the effect of preventing the further ingress of fluid in the space *d*, and also preventing the fluid in said space running out through the aperture *e* on account of the protrusion of the extension portion *c*¹, *c*², described. By reason of the dip chamber *c* 105 forming the wall between the two levels of ink, it is obvious that the withdrawal of said dip chamber will enable the vessel *a*, as well as the hood itself, to be effectually and conveniently cleaned, when desired.

100

105

110

I claim:—

In an ink stand, a reservoir, a plug forming the front of said reservoir and removable therefrom, a dip chamber integral with and 5 extending inwardly from the plug in a downward direction, and a horizontal extension upon said dip chamber and on a level with the bottom thereof, said extension having a horizontal passage connecting the reservoir

and the dip chamber, substantially as herein 10 set forth.

In witness whereof I have hereunto set my hand in presence of two witnesses.

ARTHUR SIDNEY PETERS.
